UNITED STATES PATENT OFFICE.

HENRY W. A. LEHNERT, OF NEW YORK, N. Y.

SHOWER-BATH.

1,116,897.

Specification of Letters Patent. Patented Nov. 10, 1914.

Application filed July 22, 1910. Serial No. 573,179.

To all whom it may concern:

Be it known that I, HENRY W. A. LEHNERT, a citizen of the United States, residing at the city, county, and State of New York, have invented certain new and useful Improvements in Shower-Baths, of which the following is a specification.

My present improvement in shower baths relates to an attachment adapted to be permanently connected to any ordinary bath tub faucet and to any ordinary shower bath fixture so that water can be delivered unmistakably at will either to the shower or to the tub.

In the drawings, which show one of the forms which my invention may take, Figure 1 shows the attachment applied to an ordinary bath-tub faucet and shower-bath fixture; Fig. 2 is a side elevation of the tub faucet and my attachment disconnected from the tub and shower; Fig. 3 is a front elevation of same looking in the direction of the arrow in Fig. 2; Fig. 4 is a vertical section partly in elevation through my attachment, showing also the mouth of the tub faucet and further showing the plug of the attachment positioned with its handle pointing downward to deliver from the faucet to the tub; Fig. 5 is a view similar to Fig. 4 except that the plug and its handle have been turned upwardly and away from the tub through an angle of 90°, in which position the attachment delivers from the faucet to the shower; and Fig. 6 is a top plan of the attachment looking in the direction of the arrow in Fig. 5 omitting the plug and its handle.

I will now describe the devices of the drawings, reserving it to the claim to point out the novel features and to define the scope of the invention, it being understood that the claim will be given due range of equivalents.

1 is the bath tub faucet which may be of any usual type, that shown delivering either hot or cold water or both from its mouth 1^a.

2 designates my attachment, the details of which will next be described, said attachment being secured to the bath tub faucet and being connected to the shower 3 by a pipe connection which may conveniently include a rubber tube 4. The attachment proper consists of a casing 5 having a conical opening extending horizontally through it forming a seat or chamber for a conical plug 6 having elbow handle 7. The plug is

held rotatably in position by the usual nut 8 and yielding washer 9. The casing has an inlet orifice 10 receiving the water from the faucet and delivering down through the upper part of the casing to its conical seat. It further has two outlet orifices in the same vertical zone as the aforesaid inlet orifice 10 and leading from the conical seat, one of them 11 delivering downwardly to the tub and being therefore conveniently termed the tub orifice of the casing, and the other 12 delivering horizontally or outwardly through the front of the casing to deliver to the shower and being therefore conveniently termed the shower orifice of the casing. The top of the casing expands into a horizontal table 14 having slots 14^a at its four corners and a recess 14^b in its top at the mouth of the inlet orifice 10 to receive a rubber washer 15.

16 designates U bolts adapted to straddle the tub faucet and to support the attachment therefrom by passing the threaded ends of the bolts through the slots 14^a and applying the nuts 16^a underneath the table 14. By taking up on these nuts, the washer 15 is clamped between the mouth 1^a of the faucet and the table of the attachment, which is thereupon secured water-tight to the faucet.

The plug 6 has a through port 17 extending completely through it paralleling the handle 7 and connecting the inlet orifice 10 and the tub orifice 11 of the casing when said handle points downwardly toward the tub as shown in Figs. 1 to 4. The plug further has a partial port 18 leading from the outside of the plug into the through port at right angles thereto, the mouth of said partial port being located at one side of the vertical zone, above mentioned as including the inlet and outlet orifices of the casing. The result is that the mouth of this partial port is sealed by the conical seat of the casing except at the place 5^a where the seat is cut away. By means of this cut-away portion, the inlet orifice 10 is connected with the partial port 18 and therefore delivers into said port and thence delivers by way of the through port 17 to the shower outlet of the casing, and consequently to the shower.

This, it will be noted, occurs when the handle 7 is in horizontal position pointing outwardly away from the end of the tub and toward the shower. On the other hand, when the handle 7 is in vertical position pointing downward, the mouth of the partial port 18 is positioned as shown in Fig. 4

where it is sealed by the conical seat of the casing. Therefore, no water can get to the shower. On the other hand, the tub is being supplied because the through port 17 is connecting the inlet orifice 10 of the casing and the tub orifice 11.

After the attachment has been secured as described to the particular faucet and connected with the shower by rubber tubes 4, 10 the operation will be as follows. When the handle 7 of the attachment is turned downwardly or toward the tub, the through port 17 in the plug being in vertical alinement with the inlet orifice 10 and the tub orifice 11 of the casing, it follows that the attachment will deliver to the tub. On the other hand, it cannot deliver to the shower because the mouth of the partial orifice 18 is seen from Fig. 4 to be sealed by the seat of 20 the casing. Next, to deliver water to the shower, the handle is moved through 90° into horizontal position pointing toward the shower. This rotates the plug so that the through port 17 is now horizontal and the partial port 18 is vertical as shown in Fig. 25 5, with its mouth uncovered at the cut-away portion 5^a of the casing, so that the water delivers from the inlet orifice 10 of the casing through said partial port into the 30 through port and thence horizontally outward through the shower orifice 12 of the casing to the shower. In this position of the handle and plug, it will be noted that no water can be delivered to the tub because 35 both ends of the through port are sealed by the conical seat. In short, the attachment is such that its operation to deliver water either to tub or shower at will is unmistakable. Thus, to deliver to the tub, the handle 40 7 is pointed down toward the tub and to de-

liver to the shower it is pointed horizontally toward the shower.

What I claim is:

An attachment for use in combination with a tub faucet and a shower bath, said 45 attachment having a casing the upper part of which consists of a horizontally extending table with openings at its corners, U bolts straddling the faucet, the threaded ends of which are received downwardly through the 50 openings in the table, and nuts co-acting with said threaded ends underneath the table, said casing below the table having a tubular seat extending horizontally through it, a plug rotatably fitting said seat, an inlet 55 orifice leading downwardly from the table to said tubular seat and connecting with the mouth of the faucet, said casing further having two outlet orifices leading from the seat, one downwardly to the tub and the other 60 outwardly to the shower, and said plug having a through port connecting the inlet orifice and the tub orifice at one position of rotation of the plug and further having a partial port leading into the through port, the 65 mouth of the partial port being located at one side of the through port to be normally sealed by the seat of the casing, said seat being cut away at one place to uncover the mouth of the partial port and connect it 70 with the inlet orifice of the casing when the plug has been rotated into a position which connects its through port with the shower orifice of the casing.

In testimony whereof, I affix my signature 75 in presence of two witnesses.

HENRY W. A. LEHNERT.
